Attorney.

UNITED STATES PATENT OFFICE.

THOMAS N. COFFELDER, OF EDGEWOOD, PENNSYLVANIA, ASSIGNOR TO LIBERTY RADIATOR COMPANY, OF PITTSBURGH, PENNSYLVANIA, A CORPORATION OF PENNSYLVANIA.

METHOD OF CONSTRUCTING AND ASSEMBLING RADIATOR-CORES.

1,367,019.

Specification of Letters Patent.

Patented Feb. 1, 1921.

Application filed July 1, 1918. Serial No. 242,743.

To all whom it may concern:

Be it known that I, THOMAS N. COFFELDER, a citizen of the United States, and a resident of Edgewood, in the county of Allegheny 5 and State of Pennsylvania, have invented a certain new and useful Method of Constructing and Assembling Radiator-Cores, of which the following is a full, clear, and exact description, reference being had to the 10 accompanying drawings, forming a part of this specification.

The present invention relates to a new and improved method of constructing and assembling cores for the radiators of motor 15 vehicles, aeroplanes, etc.

It has heretofore been the practice in the assembly of radiator cores to assemble the tubes and fins temporarily in the desired spaced relation, and then to dip the structure 20 in solder, thus permanently securing the assembly. The practice of this method, however, entails the use of a large quantity of solder, which serves only to secure the assembly and is otherwise of detrimental effect 25 in the functioning of the device for the reason that the accumulated quantities of solder on the tubes and fins interfere more or less seriously with heat radiation, and also add disadvantageously to the weight of the 30 device.

The object of my invention is, therefore, to provide a method of constructing and assembling radiator cores whereby the necessity for the use of solder to secure the 35 proper assembly of the tubes and fins entering into the core construction is obviated, the peculiar construction of the radiator tubes and fins and the mechanical assembly thereof, overcoming the need therefor, thus 40 reducing the weight and increasing the efficiency of the core.

In the drawings:—

Figure 1 is a perspective of tubes and fins in the process of assembly in accordance with 45 the present invention.

Figs. 2, 3 and 4 are detailed views illustrating various steps in assembling tubes and fins in accordance with the present invention.

Fig. 5 is a fragmentary elevation illustrating the positioning of a fin upon the tube.

The parts of a radiator core constructed for assembly in accordance with the present

invention, and as typically illustrated in 55 the drawings, comprise tubes 1, having seamed edges 2, the said edges being provided with notches 3 at regularly spaced intervals. Each of said tubes comprises a single sheet of metal folded together, the edges 60 thereof being internally soldered to form the seam 2. The tubes as thus constructed, and as embodying an essential requisite of this invention, have entirely straight, smooth and unobstructed outer surfaces; they have 65 also straight, smooth and unobstructed inner surfaces. Said parts comprise also for assembly with the tubes fins 4, which have transverse slots 5, within which the tubes 1 are adapted to fit. The slots 5, as arranged 70 for tubes of the preferred construction, illustrated in the drawings, extend approximately from the front to the rear edges of the fins, but leave the said front and rear edges 6 and 7, respectively, continuous and 75 unbroken as shown. At the sides of the slots 5 are flanges 8 which converge toward their free edges.

In assembling tubes and fins having the characteristic features above described, the 80 required number of tubes entering into the construction of the desired core is preferably placed on fingers or mandrels 9, with corresponding notches 3 of the several tubes in alinement. By means of the mandrels 9 the 85 tubes are held in proper spaced relation to each other, and are stiffened to prevent buckling during the application of the fins. A fin is then moved longitudinally along the tubes, as indicated in Fig. 5, the latter entering and passing through the slots of the former, until the fin has reached the desired point upon the tubes, in which position it is illustrated in Fig. 2. As thus placed upon the tubes the front edge 6 of the fin is opposite alined notches 3, in the front edges 2 of the tubes. The fin is then moved transversely of the tubes, causing the front of 90 the fin to enter into the notches 3, thereby interlocking the front edges of the tubes and 95 fins, as indicated in Fig. 3. In order to maintain this interlock the rear edge 7 of the fin is folded over against the rear edges of the tubes as indicated at 10, in Fig. 4.

This may not, however, in all cases be essential, as it will be understood that the converging flanges 8 press positively against the sides of the tubes thereby coöperating 100

frictionally to sustain the assembly. The converging flanges 8 by thus providing the positive contact between the fins and tubes required for effective radiation, further permit the making of the slots somewhat wider than the thickness of the tubes, thus facilitating the entrance of the tubes in the slots in assembling the same in the above manner. Such flanges are not, however, entirely essential, as the slots may be formed to contact directly with the tubes. Further fins, to the number required for the core are then applied in the same manner. The assembly of the fins upon the tubes, as above set forth, it will be understood, may be accomplished either manually or by any suitable mechanism, such for instance, as is particularly set forth in my pending application, Serial Number 227,261, filed April 8, 1918. It will, however, be necessary ordinarily, both for properly stiffening and sustaining the tubes and for holding the same in proper spaced relation, to employ fingers or mandrels 9, as illustrated in the drawings herein. While, for convenience of assembling, it is preferred to hold the series of tubes stationary and move the fins longitudinally and transversely thereon, the operation may be reversed, that is, the fins held stationary and the tubes moved endwise through the slots in the fins and then transversely therein, the essential features of the present method comprising the relative positioning of the fins longitudinally along the tubes and then transversely relative to the tubes to interlock the same.

The assembly of a radiator core in accordance with the present invention, it will be seen, may be accomplished with a minimum of labor and material, it being only necessary to space the fins upon the tubes by moving the same longitudinally thereon and to interlock the fins and tubes by moving the fins transversely of the tubes into the notches thereof. In this manner of assembly the use of solder for permanently maintaining the tubes and fins in proper spaced relation is entirely obviated, this function being mechanically performed by the interlocking of the parts.

Having thus fully described my invention, what I claim as new and desire to secure by Letters Patent is:—

1. The method of assembling a radiator core, comprising tubes each of which has notches at intervals along one of its edges, and fins each of which has slots arranged to receive said tubes, consisting in supporting a series of tubes in parallel relation and properly spaced with corresponding notches of the several tubes in alinement, moving said fins longitudinally relative to said tubes, to space the same thereon, with one edge of each fin opposite alined notches in the tubes, and then moving the fin trans-

versely relative to the tubes to cause the edge of the fin to enter into alined notches in the tubes to interlock the tubes and fins

2. The method of assembling a radiator core comprising tubes each of which has notches at intervals along one of its edges, and fins each of which has slots arranged to receive said tubes, consisting of supporting the tubes internally with corresponding notches of the several tubes in alinement, moving said fins longitudinally relative to said tubes to space the same thereon with one edge of each fin opposite alined notches in the tubes, then moving the fins transversely relative to the tubes to cause the edges of the fins to enter into alined notches in the tubes to interlock the tubes and fins and then removing the internal supports from the tubes.

3. The method of assembling a radiator core comprising tubes each of which has notches at intervals along one of its edges, and fins each of which has slots arranged to receive said tubes, consisting in supporting a number of tubes with corresponding notches of the several tubes in alinement, moving successive fins longitudinally relative to the tubes to space the same thereon with one edge of each fin opposite alined notches in the tubes, then moving the fins transversely relative to the tubes to cause the edges of the fins to enter into alined notches in the tubes to interlock the tubes and fins, and then folding the other edges of the fins against the other edges of the tubes to secure the same.

4. The method of assembling a radiator core, comprising tubes each of which has notches at intervals along one of its edges, and fins each of which has slots arranged to receive said tubes, consisting in supporting a series of said tubes properly spaced and in parallel relation with corresponding notches of the several tubes in alinement, moving a fin longitudinally relative to said tubes, to space the same thereon, with one edge opposite a row of alined notches in the tubes, then moving said fin transversely relative to the tubes to cause its edge to enter into the alined notches in the tubes to interlock the tubes and fin, and then repeating said operations with individual fins, interlocking each successive fin in the alined notches adjacent the preceding fin until the required number of fins have been placed upon the tubes.

5. The method of assembling a radiator core, comprising tubes each of which has notches at intervals along one of its edges, and fins each of which has slots arranged to receive said tubes, consisting of supporting the tubes internally with corresponding notches of the several tubes in alinement, next moving a fin longitudinally relative to said tubes to space the same thereon with

one edge opposite the alined notches at the far ends of the tubes, then moving the said fin transversely relative to the tubes to cause the edge of the fin to enter into said notches to interlock the fin with said tubes, then repeating said operations with individual fins, interlocking each successive fin in the alined notches adjacent the preceding fin, until the required number of fins have been placed upon the tubes and then removing the internal supports from the tubes.

6. The method of assembling a radiator core comprising tubes each of which has notches at intervals along one of its edges, and fins each of which has slots arranged to receive said tubes, consisting in supporting a number of tubes with corresponding notches of the several tubes in alinement, then moving a fin longitudinally relative to said tubes to space the same thereon with one edge opposite alined notches at the far ends of the tubes, then moving said fin transversely relative to the tubes to cause the edge of the fin to enter into said notches to interlock the fin with said tubes, then folding the other edge of the fin against the other edges of the tubes to secure the same, and then repeating said operations with individual fins, interlocking each successive fin in the alined notches adjacent the preceding fin, until the required number of fins have been placed upon the tubes.

7. The method of assembling a radiator core comprising tubes, each of which has notches at intervals along one of its edges, and fins each of which has slots arranged to receive said tubes, consisting of supporting the tubes internally with corresponding

notches of the several tubes in alinement, moving said fins longitudinally relative to said tubes to space the same thereon with one edge of each fin opposite alined notches in the tubes, then moving the fins transversely relative to the tubes to cause the edges of the fins to enter into alined notches in the tubes to interlock the tubes and fins, then folding the other edges of the fins against the other edges of the tubes to secure the same, and then removing the internal supports from the tubes.

8. The method of assembling a radiator core comprising tubes, each of which has notches at intervals along one of its edges, and fins each of which has slots arranged to receive said tubes, consisting of supporting the tubes internally with corresponding notches of the several tubes in alinement, next moving a fin longitudinally relative to said tubes to space the same thereon with one edge opposite the alined notches at the far ends of the tubes, then moving the said fin transversely relative to the tubes to cause the edge of the fin to enter into said notches to interlock the fin with said tubes, then folding the other edge of the fin against the other edges of the tubes to secure the same, then repeating said operations with individual fins, interlocking each successive fin in the alined notches adjacent the preceding fin, until the required number of fins have been placed upon the tubes, and then removing the internal supports from the tubes.

THOMAS N. COFFELDER.
